H. C. ADAMS

SAFETY FUSE FOR ELECTRICAL FLATIRONS

Filed Feb. 19, 1923

Patented Sept. 15, 1925.

1,553,843

UNITED STATES PATENT OFFICE.

HAROLD C. ADAMS, OF MINNEAPOLIS, MINNESOTA.

SAFETY FUSE FOR ELECTRICAL FLATIRONS.

Application filed February 19, 1923. Serial No. 619,842.

To all whom it may concern:

Be it known that I, HAROLD C. ADAMS, a citizen of the United States, residing at Minneapolis, in the county of Hennepin and 5 State of Minnesota, have invented certain new and useful Improvements in Safety Fuses for Electrical Flatirons; and I do hereby declare the following to be a full, clear, and exact description of the invention, 10 such as will enable others skilled in the art to which it appertains to make and use the same.

My invention provides a thermally disruptive fuse for electrically heated flat- 15 irons and the like, by the use of which the current will be automatically cut off from the iron when the iron is heated beyond a predetermined maximum temperature. Generally stated, the invention consists of the 20 novel construction and arrangement of parts hereinafter described and defined in the claims.

This invention may be appropriately designated as a safety fuse, which will not be 25 disrupted by any current that the heating element of the iron will require for heating purposes, but which will be disrupted to break the current, regardless of the current flow, providing that the iron is overheated 30 or heated to a predetermined point beyond the maximum required temperature of an iron for proper use. This prevents an iron from being damaged by too high temperature or fire from being started by accidental 35 overheating of the iron, which is very likely to occur and many times has occurred when the current has been turned onto an iron and the iron then left or forgotten.

In the accompanying drawings, which 40 illustrate the invention in what is believed to be its preferred form, like characters indicate like parts throughout the several views.

Referring to the drawings:

Figure 1 is a perspective showing my invention applied to an ordinary electrical flatiron;

Fig. 2 is a side elevation showing the rear portion of the flatiron and showing the receiving socket of the safety device in vertical section;

Fig. 3 is a horizontal section taken on the line 3—3 of Fig. 2;

Fig. 4 is a perspective showing the socket 55 of the safety device;

Fig. 5 is a perspective showing the detachable head of the safety device;

Fig. 6 is a perspective showing the plug or removable element of the safety device;

Fig. 7 is an enlarged plan view of the 60 head of the safety device; and

Fig. 8 is a diagram illustrating the wiring and manner in which the safety device is connected in series with the heating element of the iron.

The numeral 9 indicates an ordinary electrical flatiron having the customary heating element 10, handle 11, and lead wire socket 12. The numeral 13 indicates the customary 70 terminal contact head of the supply circuit 14, which latter is shown within the usual cable 15. In Fig. 8, a source of electrical energy of the circuit to the heating element is indicated by the numeral 16 and is there 75 shown as a battery, whereas, in practice, it would be a commercial electric circuit.

As a means for applying the safety device to the iron, a metal socket or casing 17, preferably of brass and of rectangular form, is directly applied to the rear end portion of 80 the iron 9. This socket 17 is open at its top and has outturned ears 18 that adapt it to be directly secured to the rear end of the base of the iron by screws 19. Between the ears 18, the socket 17 has a large opening 20 85 that opens directly against the adjacent rear end of the iron.

The head 21 of the safety device is also 90 preferably rectangular and of metal filled with an insulating material 22 that holds and spaces apart two pairs 23 and 24 of spring clamp acting lead terminals.

The cartridge or fusible element of the safety device, as preferably designed, comprises a glass tube 25, onto the ends of which 95 are telescoped metallic caps 26, preferably of copper. The fusible element of this cartridge is in the form of a wire or small rod 27 of a metal having the proper relative temperature fusibility, to wit: a fusing temperature much lower than that of any of the other metallic parts. This fusible element 27 is passed axially through the heads of the caps 26 and is rigidly and electrically connected thereto by small solder masses 28. By this arrangement, the two metallic caps 105 26 form contacts that are insulated from each other except through the fusible element 27. When the cartridge is in working position, as shown in Fig. 3, the metallic 110

caps 27 are pressed down into frictional contact with the lead terminals 23 and 24 and will be securely but displaceably held thereby. Here it will be noted, attention being directed particularly to Fig. 8, that the two leads of the supply circuit 14 are connected, one to the pair of contacts 23 and the other to the pair of contacts 24, so that the fusible element 27 is connected in series with the heating element 10.

With the above arrangement, as is obvious, the current will freely flow to the heating element 10 at any and all times except when the fusible element 27 is disrupted or broken, and it is also evident that whenever the temperature of the iron, acting by radiation and conduction, fuses the element 27, the circuit to the heating element 10 will be broken and the current will be automatically cut off, thereby positively preventing the iron from being overheated or heated to the predetermined danger point.

By placing the fusible safety device at the lower rear portion of the iron, it is arranged where it will not interfere with the use of the iron and where it will be subjected to the maximum temperature of the iron.

This safety device may be applied to new irons and also may be readily applied to electric irons now in general use, at very small cost. The construction illustrated in the drawings is particularly designed for application to irons already in use.

What I claim is:

1. The combination with an electrically heated metallic body and supply circuit, of a slip socket applied to said body, and a

frictionally held detachable coupling head 40 slidably inserted into the slip socket and carrying a detachable fusible element that is electrically connected to said supply circuit in series with the heating element of said body.

2. The combination with an electrically heated metallic body and supply circuit, of a slip socket applied to said body, and a frictionally held detachable coupling head 45 slidably inserted into the slip socket and closing the same, said head carrying on its inner end a detachable fusible element that is electrically connected to said supply circuit in series with the heating element of said body, said socket having an opening at its application to said body and below said head to expose the fusible element to the 50 heat from the body.

3. The combination with an electrically heated metallic body and supply circuit, said body having a coupling socket and said circuit having a co-operating detachable coupling head, of a slip socket applied to said body, and a frictionally held detachable coupling head 60 slidably inserted into the slip socket and closing the same, said head carrying on its inner end a detachable fusible element that is electrically connected to said supply circuit in series with the heating element of said body, said socket having an opening at its application to said body and below said head to expose the fusible element to the 65 heat from the body.

In testimony whereof I affix my signature.

HAROLD C. ADAMS.
